UNITED STATES PATENT OFFICE.

JOHN A. STRANSKY, OF PUKWANA, SOUTH DAKOTA.

GERMICIDE ATTACHMENT FOR TELEPHONES.

1,329,557.

Specification of Letters Patent.

Patented Feb. 3, 1920.

Application filed February 20, 1919. Serial No. 278,197.

To all whom it may concern:

Be it known that I, JOHN A. STRANSKY, a citizen of the United States, residing at Pukwana, in the county of Brule and State 5 of South Dakota, have invented certain new and useful Improvements in Germicide Attachments for Telephones, of which the following is a specification.

The present invention comprehends generally improvements in germicide attachments for telephones and more particularly relates to a telephone mouthpiece protector.

It is the primary aim and object of this invention to provide a device of the above 15 mentioned character designed to be detachably engaged with the outer edge of a mouthpiece so as to cover the mouthpiece for preventing the accumulation of dust in the mouthpiece and for preventing the passage of moisture or other matter from the 20 mouth of a person speaking into the same and thereby in consequence prevent the spreading of contagious diseases.

It is an additional and equally important 25 object of this invention to provide a device of the above mentioned character wherein the construction is of improved form, the component parts being removably related to each other so that the antiseptic diaphragm 30 may be replaced when desired yet at the same time the parts are so constructed that they coact with each other to insure of a proper positioning and retention of the device when attached.

35 It is a more specific object of this invention to provide a device of the above mentioned character wherein the retaining member or ring is of novel construction and is formed with resilient tongues positioned to 40 removably hold an antiseptic tablet cake laterally of the inner face of the antiseptic disk-like diaphragm and within the mouthpiece.

Among the other aims and objects of this 45 invention may be recited the provision of a device of the above mentioned character with a view to compactness, and wherein the number of parts are comparatively few, the cost of construction low and the efficiency 50 high.

Other objects as well as the nature, characteristic features and scope of this invention will be more readily apparent from the following description taken in connection with 55 the accompanying drawings and pointed

out in the claims, forming a part of this specification.

The invention is clearly illustrated in the accompanying drawings, in which:

Figure 1 is a perspective view of a portion 60 of a transmitter and mouthpiece of a telephone showing the protector attached thereto.

Fig. 2 is an enlarged fragmentary longitudinal sectional view of the mouthpiece 65 showing the device in position.

Fig. 3 is a fragmentary sectional detail showing the relation of one of the retaining lugs with respect to the mouthpiece, and

Fig. 4 is an elevational detail of the retaining ring. 70

Similar characters of reference are employed in all of the above described views, to indicate corresponding parts.

Referring now, more particularly, to the 75 accompanying drawings there is illustrated a portion of a transmitter 1 of the telephone which receives the mouthpiece 2 while detachably connected to the outer edge of the mouthpiece is the improved germicide attachment or protector generally indicated by the numeral 3 designed primarily for preventing the spreading of contagious diseases by preventing the accumulation of dust and germs in the mouthpiece being 80 constructed and arranged so that the mouth of a user will not contact with the mouthpiece. 85

In the present instance, the improved protector may be said to consist of a supporting 90 and attaching member comprising an annular or ring body 4 of a diameter approximately equal to the outer diameter of the outer portion of the mouthpiece while projecting at opposed points from the periphery or outer edge of the body 4 are a plurality of resilient attaching lugs 5 designed to embrace the outer surface near the outer edge of the mouthpiece. A disk-like diaphragm 6 is now employed and is preferably 95 formed of chemically treated fibrous or silk paper which is relatively stiff and which diaphragm is arranged against the inner face of the ring body 4 and supported and retained by the lugs 5. A retaining ring is 100 now employed and is generally designated by the numeral 7 being formed of metal and of a diameter approximately equal to the diameter of the annular or ring body 4 being positioned against the opposite face of 105 110

the diaphragm 6 and retained against accidental displacement by the lugs. When the lugs are engaged with the mouthpiece this retaining ring is held against the outer edge 5 of the mouthpiece, the arrangement being clearly indicated in the drawings, the diaphragm 6 of course being clamped between the ring 7 and the ring body 4. In order to releasably retain antiseptic material within 10 in the mouthpiece without interfering with the transmission of sound, the ring 7 is formed on its inner edge with opposed spring tongues 8 which extend toward each other and at a slight angle from the plane 15 of the ring, the outer ends being slightly offset or bent as at 9 and designed to releasably and yieldingly engage the opposite faces of a cake 10 of antiseptic material, holding the latter laterally of the inner face 20 of the disk-like diaphragm 6, the arrangement being clearly indicated in Fig. 2. By the particular construction and arrangement of parts disclosed the diaphragm 6 and the rings 3 and 7 together with the tongues 8 25 of the latter are held in place and provide effectual means for retaining the antiseptic element in position laterally of the inner face of the removable disk shaped diaphragm and within the mouthpiece. 30 By this arrangement also the parts are readily separable for renewal or repairs or to replace an exhausted antiseptic element. The antiseptic elements may be renewed without disconnecting the diaphragm 6 or 35 the inner ring 7 from the outer ring 3.

It is believed in view of the foregoing description that a further detailed descrip-

tion of the operation of the invention is entirely unnecessary. Likewise, it is believed that the advantages of the invention will be 40 readily apparent.

Still further embodiments of the invention than those herein especially defined may be resorted to as conditions or preference may dictate, as may be in keeping with 45 the hereto appended claims.

Having thus fully described the invention what is claimed as new and desired to be secured by Letters Patent, is:—

1. In a telephone mouthpiece protector, 50 the combination with an attaching and supporting member, and a diaphragm, of a diaphragm retaining ring supported and retained by the supporting member, a cake of antiseptic material, and an engaging means 55 on the ring for yieldingly and removably engaging the cake and supporting it laterally of the inner surface of the diaphragm and within the mouthpiece.

2. In a telephone mouthpiece protector, 60 the combination with an attaching and supporting member and a diaphragm arranged and supported against the inner surface of the supporting member, of a diaphragm retaining ring supported and retained by 65 the supporting member, a cake of antiseptic material, and resilient tongues integral with the inner edge of the retaining ring and removably engaging the cake and supporting it laterally of the inner surface of the dia- 70 phragm and within the mouthpiece.

In testimony whereof I affix my signature hereto.

JOHN A. STRANSKY.
